UNITED STATES PATENT OFFICE.

PATENTED

ARIADNA B. MERCIER, OF PROVIDENCE, RHODE ISLAND.

IMPROVED CLOTHES-WASHER.

Specification forming part of Letters Patent No. 56,773, dated July 31, 1866.

To all whom it may concern:

Be it known that I, ARIADNA B. MERCIER, of Providence, in the county of Providence and State of Rhode Island, have invented a new and useful Improvement in Clothes-Washers; and I do hereby declare that the following is a full, clear, and exact description of the same, reference being had to the accompanying drawings, forming a part of this specification, in which—

Figure 1 is a perspective view. Figs. 2, 3, and 4 are parts of my invention.

In the accompanying drawings, A, Figs. 1 and 4, is a plate of wood or metal made to fit easily in a clothes-boiler of any shape. This plate is perforated with small holes, having one large hole in the center, Fig. 4. This hole is provided with a stopper, B, Figs. 1 and 2.

On the under side of plate A are four legs, for the purpose of keeping it a suitable distance from the bottom of a clothes-boiler when in use, as shown by dotted lines on Figs. 2 and 3.

What my invention consists in, and to use the same, is, when the space under plate A, which is formed by the application of my invention in a boiler, is filled with water, and the stopper B being in the large hole, the clothes to be washed are placed on either side and around this stopper. The boiler is then placed over a fire. As soon as the water commences to boil, the stopper B is removed, the

center hole being so large that the ebullition by boiling causes a jet of water to be forced up through this hole, and, falling back on the clothes, rinsing them, and runs down through the small holes into the space under plate A, making a continuous revolution of the water, which, in connection with the steam, removes all dirt from the clothes.

By the use of my invention clothes can be washed without rubbing them and in one-quarter the time, rendering them whiter and saving the fabric, as it is not necessary to use a wash-board in connection with my invention, the advantages of which can be plainly seen, as rubbing the clothes destroys them more or less without rendering them as clean, and being a laborious process.

With my invention, one hour boiling, the clothes can be put into the last rinsing-water, wrung out, and hung on the line to dry.

I do not claim the boiler for boiling clothes in; but

What I do claim as my invention, and wish to secure by Letters Patent, is—

The combination of a perforated plate with a stopper, in the manner set forth, and for the purpose specified.

ARIADNA B. MERCIER.
